UNITED STATES PATENT OFFICE.

WILLIAM H. GOSS, OF STONINGTON, MAINE.

DESIGN FOR A GARMENT-HOOK.

SPECIFICATION forming part of Design No. 34,223, dated March 12, 1901.

Application filed February 8, 1901. Serial No. 46,588. Term of patent 7 years.

To all whom it may concern:

Be it known that I, WILLIAM H. GOSS, a citizen of the United States, and a resident of Stonington, in the county of Hancock and State of Maine, have invented and produced a new and original Design for a Garment-Hook, of which the following is a full, clear, and exact description.

Reference is to be had to the accompanying drawings, forming a part of this specification, in which similar characters of reference indicate corresponding parts in both the figures.

Figure 1 is a side view of a garment-hook, showing my design; and Fig. 2 is a front view thereof.

The leading features of my design for a garment-hook consist in the body portion, the two upwardly-curved members extended from the body one above the other, the lower curved member being shorter than the upper curved member, and the upper member consisting of two straight sections, one section being inclined upward and outward from the top of the body and the other section being inclined downward and outward and terminating inward of the end of the upper curved member.

Referring particularly to the drawings, 1 designates the body portion, from which upwardly-curved hook members 2 and 3 extend, the upper hook member 3 being somewhat 30 longer than the lower hook member 2. The upper member extended from the body consists of a section 4, that is inclined upward and forward, and from the end of this section 4 a section 5 is inclined downward and forward or at substantially right angles to the section 4, and the end of this section 5 is inward of the end of the hook member 3, and wing-like portions 6 extend laterally from the body portion. 35 40

Having thus described my invention, I claim as new and desire to secure by Letters Patent—

The design for a garment-hook as herein shown and described. 45

In testimony whereof I have signed my name to this specification in the presence of two subscribing witnesses.

WILLIAM H. GOSS.
